UNITED STATES PATENT OFFICE.

GEORGE R. RATHBUN, OF PONTIAC, MICHIGAN.

ROTARY VALVE.

Application filed June 21, 1926. Serial No. 117,255.

This invention relates to rotary valves for internal combustion engines, and has for its object to provide a simple and cheap device which will avoid many of the objectionable features commonly ascribed to rotary valve design and which have been heretofore met with in internal combustion practice in the use of rotary valves.

One of the important requirements which it is an object of this invention to meet is that of cooling the valve structure, so as to relieve undue or uneven expansion of the rotary member of the valve in its housing, and to prevent burning of the rotor; and another object of the invention is to obtain in a novel and effective manner a preheating of the inlet charge to the engine.

Still further, the said invention contemplates the admission of inlet gases to the cylinders of the engine through a plurality of openings, so that such charge enters the cylinders in a number of jets tending to provide a more evenly distributed mixture in the cylinders and at the same time to admit of a free and uninterrupted exhausting of the products of combustion from the cylinders.

More particularly, it is an object of the invention to provide a built up rotary valve wherein a central rotary exhaust pipe is provided with sleeves forming the valves proper and having exhaust ports therein opening into the said pipe and inlet ports in the form of perforations opening into cavities within the said sleeves, the said sleeves being provided with annular series of passages in the walls thereof through which inlet gases are admitted to the said cavities whilst absorbing heat from the walls of said valves proper.

Still further objects subsidiary to or resulting from the aforesaid objects or from the construction or operation of the invention as it may be carried into effect, will become apparent as the said invention is hereinafter further disclosed.

In carrying the said invention into effect, I may provide a novel construction and arrangement of parts more particularly described and ascertained hereinafter, by way of example, having reference to the accompanying drawing, wherein—

Figure 1 is a horizontal section through the cylinders and valve casing of an engine, illustrating in plan and partly in section a rotary valve embodying the said invention;

Figure 2 is a vertical section through the valve casing;

Figure 3 is a transverse section taken on the line 3^x—3^x, Figure 1;

Figure 4 is a detail perspective view of one of the valve sleeves removed; and

Figure 5 is a detail perspective view of one of said sleeves shown partly in section to indicate the passageways therein.

Similar characters of reference indicate similar parts in the several figures of the drawing.

A, B, C and D represent the cylinders of a four cylinder internal combustion engine, the cylinder head of which is provided with a tubular valve casing 1, and a, b, c and d are combined inlet and exhaust ports establishing communication between the said valve casing and the said cylinders. The said valve casing is indicated as being provided with a liner 2 similarly ported, and intermediate of the length of the said valve casing is an inlet pipe 3.

4 is a rotary exhaust pipe of substantially smaller diameter than the lining of the valve casing and provided at one end with a closure in the form of a bevel gear 5 through which the said exhaust pipe may be rotated as by the pinion 6.

Corresponding with the four cylinders are four sleeves or valves proper 7, 8, 9 and 10, these sleeves being provided with exhaust ports 11, and the exhaust pipe 4 being coincidentally ported, the arrangement of the exhaust ports being in accordance with whatever the firing order of the cylinders may be as will be well understood by those conversant with the art to which this invention appertains. The said sleeves are also provided with inlet ports 12 each in the form of a plurality of orifices extending more or less radially through the wall of the sleeve over a desired area approximating that of the area of the exhaust ports and within each sleeve is a cavity 13 of substantial size with which communicate annular series of

passages 14 in the walls of the said sleeves, so that the said walls may be said to be of cellular construction. The outer ends of the two end sleeves 7 and 10 may however, be completely closed as at 7^a and 10^a for reasons which will be quite apparent when it is understood that the said passages 14 form the means whereby inlet gases from the inlet 3 are permitted to pass to the several cavities 13 of the said sleeves, the closing of the pas-

sages at the outer ends of the sleeves 7 and 10 preventing escape of the inlet gases therefrom.

It will be readily understood without detailed explanation how such inlet gases pass by way of the passages 14 cavities 13 and inlet ports 12 to the cylinders as the rotary valve as a whole turns in the valve casing, and it will be noted that this passage of the cold inlet gases through the walls of the sleeves will have a very marked cooling effect thereon, and that accordingly the inlet gases will be heated and in a readily combustible condition. This condition is added to by the fact that considerable turbulence in splitting up of the inlet gases as they enter the cylinders through the orifices of the inlet ports 12 takes place.

A number of cylinders or the particular timing arrangement of the valves is of course a matter of convenience and desirability, and the invention may be developed within the scope of the following claims without departing from the essential features of the said invention, wherefore it is desired that the specification and drawing be read as merely illustrative and not in a limiting sense, except as necessitated by the prior art.

What I claim is:—

- 30 1. In a rotary valve for internal combustion engines, an exhaust pipe extending through the center of said valve, and a cylindrical casing enclosing said valve, said valve having inlet and exhaust ports therein, and a plurality of inlet passages extending longitudinally through the wall of said valve exterior of said exhaust pipe to said inlet port.
- 35 2. In an internal combustion engine, a rotary valve device comprising a cylindrical valve casing having an inlet port, a rotary

exhaust pipe housed therein, a sleeve mounted on said pipe and having a cavity in its inner wall, radial ports communicating with said cavity and adapted for communication with said inlet port, longitudinal passages through the wall of said sleeve and communicating with said cavity, said sleeve and exhaust pipe having coincident exhaust ports.

3. In an internal combustion engine, a rotary valve device comprising a cylindrical valve casing having an inlet port, a rotary exhaust pipe housed therein, a sleeve forming the valve proper mounted on said pipe, said sleeve and pipe having coincident exhaust ports therethrough and said sleeve having inlet ports opening radially thereof, and annular series of longitudinal passages affording communication between the inlet port of the valve casing and the inlet ports of said sleeve, said inlet ports being in the form of a plurality of small orifices extending over a substantial area.

4. In an internal combustion engine, a rotary valve device comprising a cylindrical valve casing having an inlet port, a rotary exhaust pipe housed therein, a sleeve forming the valve proper mounted on said pipe, said sleeve and pipe having coincident exhaust ports therethrough and said sleeve having inlet ports opening radially thereof, and annular series of longitudinal passages affording communication between the inlet port of the valve casing and the inlet ports of said sleeve, said sleeve having a cavity in its inner wall and in communication with the inlet ports of said sleeve, said longitudinal passages extending from the ends of said sleeve to said cavity.

In testimony whereof I affix my signature.

GEORGE F. RATHBUN.
